Almanach für die alte Kirch. Bist. Bistumsg.

Letters Patent.

Also, he has referred to in those letters Poland and making
part of the same, or containing a description of the orders of the said
General M. Kirk & Genl Kirk. I have no idea of these papers myself, & the use
of having a copy of them. Through however, by a favorable coincidence
will I do you the favor of sending these letters & enclosing all.

the flue in inner walls and receding a distance to cover the surface of a
 much of the front wall surface between the extremities of the back sides
 of the inner walls, this wall where upper and main are then covered by
 the front plate being all of uniform convenient height, the front top the
 back side plates of the stove (which must be plain plates) resting them
 respectively on the back plate, so that the back & side walls of the inner
 wall, the front plate of the stove (also or named as thought proper)
 must correspond in size with the back plate, except that its height
 need not be extended as far as may be found necessary to make to join
 the uppermost plate of all hereafter described, and it must have
 the proper openings for the grates for an even immediately on the
 plate, the iron must be constructed to touch the front plate only, the
 fastened in its position by one or more screw bolts, or as admitted
 the first heat to pass all round it, the top plate of the stove must correspond
 in size with the bottom plate, and have properly shaped designed
 holes to admit the bottom or bottom of one or more boiler & pipe hole
 over the side of the iron, around each of the holes in the top plate of
 the stove, let these ledges or shoulders to extend three or more inches
 upward, now build up the back and side walls of the outer flue
 square and so much of the front as may be necessary until they reach
 say three inches higher than the top plate of the stove, then let one
 iron plate cover the entire structure, and resting on the tops of the walls
 and of the front plate, (of course of a uniform convenient height) this
 cast iron plate has in such holes or openings in it as may be necessary
 to receive the ledges or shoulders above mentioned, with having another
 hole or opening say one third larger than the pipe hole, in the rear of the
 pipe hole to communicate with a passage way etc, with the space
 open between the iron and uppermost cast iron plate between
 the outer & inner walls of the stove, this last hole or opening of the
 uppermost cast iron plate, the air admitted from without by a tube or
 tube, or other opening in the back outer wall, as above described,
 located in a pipe between the wall & stove, while it is kept wholly
 separate from the air in the flue, and is ready to be diffused

1135X

1135
Apparatus of a fire-proofed house, throughout the house,
the documents, as an important part of a patent, the
combination of what are usually known as chimney with them
carrying them, in the manner herein described, collecting and
removing all the heat thereon sent by the back side of the chimney
so as to make one fire place, and the same for the purpose
of heating the air for the house, cooking, preserving the air or
airages for small insuring.

The following is a true specification
of an said improvement as above described we have witnessed
at our hands this twenty sixth day of August in the year of
one thousand eight hundred and thirty three.
